UNITED STATES PATENT OFFICE.

JOHN MUIRHEAD, OF PITTSTON, PENNSYLVANIA.

DRILL.

SPECIFICATION forming part of Letters Patent No. 439,972, dated November 4, 1890.

Application filed June 10, 1890. Serial No. 354,904. (No model.)

To all whom it may concern:

Be it known that I, JOHN MUIRHEAD, a citizen of the United States, residing at Pittston, in the county of Luzerne and State of

5 Pennsylvania, have invented a new and useful Improvement in Drills, which improvement is fully set forth in the following specification and accompanying drawings.

My invention relates to improvements in 10 drills; and it consists, first, of a drill having a stem with enlarged portions, the latter having a tapering opening, and a groove leading thereto, in combination with a bit adapted to be held in said opening and 15 groove; second, of a drill having a screw-threaded portion of its stem provided with a movable guide-block, the latter being held in place by a key, substantially as described.

Figure 1 represents a side view of a drill 20 having a tool-holder with bits and a guiding-block as embodying my invention. Fig. 2 represents a central longitudinal sectional view of the device shown in Fig. 1. Figs. 3 and 4 represent cross-sections on lines x x 25 and y y , respectively, Fig. 1. Fig. 5 represents a perspective view of one of the bits.

Similar letters of reference indicate corresponding parts in the several figures.

Referring to the drawings, A designates a 30 drill consisting of the holder B, the stem portion C, the guiding-block D, and the bits E.

The holder B is formed of the enlarged portions F and G of the stem, the larger portion F having a series of conical or tapering openings H therein at equal distances from the center of the stem, and the smaller portion G having the grooves J, the said openings and grooves extending in the same direction and being adapted to receive, respectively, the 35 tapering necks K and the back portions L of the bits E. The shouldered portions M of the bits are in contact with one side of the said larger portion F, and on the screw-threaded ends K' of the necks K are the 40 clamping-nuts N, which bear against the holder B and reliably retain the bits in place therein.

The bits E have enlarged or widened front 45 or outer portions P, and the beveled faces of 50 their cutting-edges are the widest at the outer edge of the bit, as at Q, the said cutting-edges extending beyond the periphery of the holder.

The upper end of the stem C is provided with the usual head R and a screw-thread S for securing the drill to its operating mech- 55 anism.

The lower end of the stem has a screw-threaded portion T, on which is secured the many-sided guiding-blocks D by means of the key U, which latter is seated in the slot V of 60 the stem, and the recess or groove X of the said block D.

When it is desired to place a bit in the holder, the tapering neck K is inserted in an opening H, the back of the bit being in the 65 adjacent groove J, and the bit is pushed so that the threaded portion K' of the neck K projects from the holder, when a nut N is secured thereon so as to clamp said bit in proper position. In releasing the bit the nut is first 70 removed from the neck, and the bit is pushed outward in the line of the groove so as to remove the neck from the opening and thereby permit its release from the holder.

In operating the device the end of the stem 75 having the guiding-block D is first inserted in a small opening suitably formed in the article to be drilled, so that the said block D may serve as a guide for the drill in its reciprocating as well as rotary motion.

It will be seen that with bits formed and secured as herein described a hole or opening of uniform diameter may readily be drilled in any suitable material, the said hole also having its walls extending in the same direc- 85

Owing to the front or outer portion of the bit being the widest, the extra wear and greater strain which are at the outer part of the cutting-edge are provided for.

Having thus described my invention, what I claim as new, and desire to secure by Letters Patent, is—

1. A drill having a stem with enlarged portions forming a tool-holder, one of said portions being provided with a tapering opening and another with a groove leading from said opening, in combination with a bit having a tapering neck adapted to fit in said opening and a back adapted to fit in said groove, substantially as and for the purpose set forth.

2. A drill having a stem with enlarged portions forming a tool-holder, one of said por-

tions being provided with a tapering opening and another with a groove leading from said opening, in combination with a bit having a thickened front or outer portion and a tapering neck or shank forming a shoulder with said outer portion, thereby providing a cutting-edge of greater width than the said neck or shank, substantially as described.

3. A drill having on its stem a screw-thread-

ed portion at or near one end thereof, a movable block on said screw-threaded portion of the stem, and a key seated in a slot in said stem and in a recess in said block, substantially as described.

JOHN MUIRHEAD.
